Primary Examiner — Elizabeth J Oswecki*(74) Attorney, Agent, or Firm* — Dragon Sun Law Firm, PC; Jinggao Li, Esq.; Nathaniel Perkins**(57) CLAIM**

The ornamental design for a portable biometric safe, as shown and described.

DESCRIPTION

FIG. 1 is a top, rear and left side perspective view of a portable biometric safe showing my new design;

FIG. 2 is a top, front and right side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of the portable biometric safe taken from the circle part in FIG. 1; and,

FIG. 10 is an enlarged view of the portable biometric safe taken from the circle part in FIG. 2.

The dashed-dot lines in FIGS. 1, 2, 9 and 10 illustrate the boundary line of the enlarged portion views of FIGS. 9 and 10.
